Michael B. Dyott, of Philadelphia, Pa.
Letters Patent No. 796, Dated May 27th 1856.

The schedule referred to in these Letters Patent, and making
part of the same.

To all whom it may concern:

Be it known that I, Michael B. Dyott
of the City and County of Philadelphia and State of Penn-
sylvania have invented or produced a new and original
Design for constructing an article which embraces in its
self a Match Safe, Paperweight and Pin Cushion, and I
do hereby declare that the following is a full and exact

Des. 796

description of the same, reference being had to the annexed drawings forming part of this specification in which

Figure One is a perspective representation of the complete Design.

Figure 2, is a vertical section of the same.

Figure 3, is a perspective delineation of the safe, rubber and paper weight, the lid or cover being taken off.

Figure 4, represents the lid or cover which also constitutes the Pin cushion.

The letters of reference in each of the respective figures indicate corresponding parts of the entire Design represented in Figure one.

The nature of my invention consists in the production of a Design for a Match safe, Paper weight, and Pin cushion of such appearance as shall be agreeable to the taste of the public and at the same time being adapted to three useful purposes (To act) a safe and convenient repository for matches with its accompanying convenience for igniting them, a paper weight and Pin cushion which being combined in one article, forms a new design of utility, convenience and ornament for the various positions in which it will be required.

The base (A.) is a slab or block of metal or other heavy material coated with glass, emery, sand, or its surface otherwise roughed or corrugated so as to form a convenient and efficient place to strike the match against to ignite it, and also to be of sufficient weight to prevent papers from being scattered by the wind. This receptacle in which the matches are kept is a cylindrical Brass or other metallic device of the design substantially such as is delineated in each of the respective figures, lettered B. The lid or cover Figure 4, contains in its upper part a Pin cushion (D).

The matches (E) are represented in Figures 2 and 3 occupying

3

Des. 786

the place assigned for them and where they are perfectly safe from ignition being encased entirely in material which is incombustible.

What I claim as new and desire to secure by Letters Patent is the New Design of a combined Match safe, Paper weight and Pin Cushion, Substantially such as is represented in the Drawings and Specification herein referred to.
